UNITED STATES PATENT OFFICE.

THEODORE HAVILAND, OF LIMOGES, FRANCE.

DESIGN FOR A PLATE.

46,802.

Specification for Design.

Patented Dec. 29, 1914.

Application filed October 31, 1913. Serial No. 798,601. Term of patent 7 years.

To all whom it may concern:

Be it known that I, THEODORE HAVILAND, a citizen of the United States, residing at Limoges, in the Republic of France, have invented a new, original, and ornamental Design for Plates, of which the following is a specification, reference being had to the accompanying drawing, forming a part thereof.

The figure is a plan view of a plate par-

tially broken away, illustrating my new design.

I claim—

The ornamental design for a plate as shown.

THEODORE HAVILAND.
